UNITED STATES PATENT OFFICE

CHARLES HAGGERTY, OF PROVIDENCE, RHODE ISLAND, ASSIGNOR TO NEW ENGLAND BUTT COMPANY, OF PROVIDENCE, RHODE ISLAND, A CORPORATION OF RHODE ISLAND

CARRIER FOR BRAIDING MACHINES

Application filed July 1, 1929. Serial No. 375,077.

This invention relates to an improved construction of carrier for braiding machines; and has for its object to provide in such a carrier a coil spring arranged to produce a quicker acting and more sensitive and reliable tension for controlling the yarn feed than was possible with the old style gravity tension weight.

A further object of the invention is to provide a latch lifting rod which is guided on the weight standard and on which rod is mounted a coil spring to act upon the weight.

The invention further consists in forming the lift rod in U-shape, one end of one arm being attached to the feed control latch and the other arm carrying a coil spring to act upon the tension weight.

With these and other objects in view, the invention consists of certain novel features of construction, as will be more fully described, and particularly pointed out in the appended claims.

In the accompanying drawings:

Fig. 1 is a side elevation showing my improved construction of carrier with the tension weight in partly lifted position and with the latch in engagement.

Fig. 2 is a view showing the base portion of the package as riding on the rocker latch, the latch being withdrawn from engagement with the ratchet teeth of the package.

Fig. 3 is a front view partly in section with the package and latch removed showing the bifurcated lift rod as being guided on the weight standard and showing the coil spring on one arm of the lift rod.

Fig. 4 is the same as Fig. 3 showing the weight in raised position in engagement with the abutment on one arm of the lift rod and the spring compressed on the other arm of the rod by the weight.

It is found in the practical construction and operation of braider carriers of this character, of advantage to construct a lift rod for the yarn let off latch with a pair of arms, one arm being connected to the latch while the other arm is guided in the weight standard and is arranged to carry a coil spring to exert a tension on the weight to assist in accelerating its return movement after

having operated the let off to release more yarn from the package and the following is a detailed description of the present embodiment of my invention and showing one construction of carrier by which these advantageous results may be accomplished:

With reference to the drawings, 10 designates the body of the carrier which is provided with a package spindle 11 on which the yarn package 12 may be mounted. 13 designates the weight standard which extends upward from the body member and which is preferably cast integral with the body and is of the usual oval shape in cross section to receive and guide the yarn tension weight 14 to slide vertically thereon.

This standard is herein shown as being provided with a front boss or lug 15 which is drilled to receive and guide the downwardly turned arm 17 of the latch lifting rod 18. This latch lift rod is preferably formed in elongated U-shape one arm 20 of which has its end 19 looped about the end 21 of the rocker latch 22 and this arm 20 is provided with an offset abutment 23 for the purpose presently described.

The upper end of this rod has a return bend 24 and the downward turned arm member thereof extends thru and is guided in the boss 15 on the standard 13. The free end 80 of this arm extends down thru an eye 25 in the weight 26 and a spring 27 is coiled about this arm 17, with its upper end 28 abutting against the boss 15 while its lower end 29 abuts against the boss 25 of the weight so that when this weight is caused by the tension of the yarn to slide upwardly on its standard 13 it compresses the spring 27 and engages the abutment 23 on the arm 20 of the lift rod to rock the latch 22 and withdraw its tooth 29 from engagement with the teeth 30 on the bottom of the package spool 24 thus releasing the package spool to rotate and permit more yarn 31, to be drawn from the package 12 and when sufficient has been drawn from this package the spring 27 acts upon the weight to quickly force it downwardly from engagement with abutment 23. This downward sliding movement of the eye 25 on the arm 17 of the lift rod, together with the 100

downward movement of the lower end portion of the spring on this arm 17 also serves to assist in accelerating the initial reengaging action of the latch with the teeth in the 5 spool 30 to arrest the releasing rotation of the package and maintain a comparatively constant tension on the yarn during a braiding operation even though the carrier is running at a high rate of speed.

10 The yarn 31 as is usual is led from the package 12 thru an eye 32 in the standard 13 down around back of the weight thence up thru the eye 33 to the point of braiding. By my improved arrangement of latch lift 15 and tension spring the yarn take up action of the tension weight is greatly accelerated over the old style gravity weight permitting the carrier to run at a much greater velocity than would be possible without the assistance of such a spring.

20 The foregoing description is directed solely towards the construction illustrated, but I desire it to be understood that I reserve the privilege of resorting to all the mechanical changes to which the device is susceptible, the invention being defined and limited only by the terms of the appended claims

I claim:

1. A carrier for braiding machines having means for mounting a yarn package thereon, a weight guiding standard, a weight 30 slideable on the standard, a latch for controlling the rotation of the package, a movable latch operating lift rod guided on said standard, a compressible coil spring on the lift 35 rod continually engaging the weight, and means whereby the lifting of the weight a predetermined distance against the spring tension lifts said rod to move the latch to 40 release the package.

2. A carrier for braiding machines having means for rotatably mounting a yarn package thereon, a weight guiding standard, a latch for controlling the release of yarn from 45 the package, a movable latch operating lift rod guided on the standard and having an abutment thereon, one end of said rod being connected to said latch, a weight slideable on the standard and arranged to engage the 50 abutment to move the latch to release the package, and a compression coil spring on the rod continually engaging the weight to accelerate its movement from yarn releasing position.

55 3. In a carrier for braiding machines, yarn package supporting means, a tension weight, a weight guide standard, a lift rod guide member on the standard, a latch for controlling the yarn release movement of the 60 package, a movable latch lift rod guided in said guide member a spring coiled about said lift rod and continually engaging with said guide member and said weight to accelerate the return of the weight after acting on the 65 rod and latch to release the package.

4. In a carrier for braiding machines, yarn package supporting means, a tension weight, a guide standard therefor, a latch for controlling the yarn release movement of the package, a movable bifurcated lift rod attached to said latch and guided on said standard, an abutment on one arm of said rod, a coil spring carried by the other arm of said rod and continually engaging said weight whereby when the weight is lifted a predetermined distance it engages said rod abutment to move the latch and release more yarn, the spring acting to accelerate the return of the weight from yarn releasing position.

5. A carrier for braiding machines, yarn package supporting means, a tension weight, a guide standard therefor, a rocker latch for controlling the feed of the yarn package, a movable bifurcated lift rod having one arm 85 attached to the latch, a weight engaging abutment on one of said arms, a coil spring carried by the other of said arms and continually engaging said weight, whereby when the weight is lifted it engages said abutment and the latch is operated to release the package and the spring is then caused to act upon the weight to accelerate its movement back from yarn releasing position.

6. In a carrier for braiding machines, yarn 95 package supporting means, a latch for controlling the yarn releasing movement of said package, a guide standard, a movable weight guided by said guide standard, a movable lift rod secured to said latch and guided at 100 one end in said standard and at the other end in said weight, and an abutment on said lift rod engageable by said weight to move the latch to release the package.

In testimony whereof I affix my signature. 105
CHARLES HAGGERTY.
